CLAIM

[21] Appl. No.: 19,612

The ornamental design for a ruler with adjustable diameter compass, as shown and described.

[22] Filed: Mar. 8, 1994

DESCRIPTION

[52] U.S. Cl. D10/62; D10/65;

D10/71

[58] Field of Search D10/62, 65, 71; 33/339,
33/387, 388, 382, 403, 483-494, 548

FIG. 1 shows a perspective view of the present invention;

FIG. 2 shows a bottom view of the present invention;

FIG. 3 shows a side view of the present invention;

FIG. 4 shows the other side view of the present invention;

FIG. 5 shows one end view of the present invention;
and,

FIG. 6 shows the other end view of the present invention.
